UNITED STATES PATENT OFFICE.

BRADLEY WOODHULL, OF DUNMORE, PENNSYLVANIA, ASSIGNOR TO THE SCRANTON STOVE WORKS, OF SCRANTON, PENNSYLVANIA.

DESIGN FOR A STOVE OR RANGE.

SPECIFICATION forming part of Design No. 28,663, dated May 17, 1898.

Application filed March 2, 1898. Serial No. 672,342. Term of patent 14 years.

To all whom it may concern:

Be it known that I, BRADLEY WOODHULL, a citizen of the United States, residing at Dunmore, in the county of Lackawanna and State 5 of Pennsylvania, have invented and produced a new and original Design for Cooking Stoves or Ranges, of which the following is a specification, reference being had to the accompanying drawing.

10 The drawing represents in perspective my design for stoves and ranges.

The leading feature of the design is the configuration and ornamentation of the stove, which is German renaissance.

15 A indicates the base; B, the legs, the base-strip being covered by scroll design having a central ornament C and at the corners above the legs the ornamentations D, the legs being covered with leaf ornamentations, as 20 shown.

E is the oven-shelf, the top of which carries a scroll design, the edge of the shelf being convex and similarly ornamented, the lower edge of the shelf following the outline 25 of the ornament on the edge.

The oven-door F is furnished with a central panel F' of scroll design, said panel being partly surrounded by a scroll-and-leaf ornamentation G. To the rear of the oven-door 30 is the reservoir-panel H, carrying a scroll-and-leaf ornamentation covering part of its surface, the lower part of said panel following the outline of said ornamentation.

Located to the front of the stove is the fire-door I, panel J, and ash-cup K, ornamented with scroll-and-leaf design and producing the effect of one long door or panel with ornamentation of unbroken design.

45 L represents the draft-door, the lower section of which is ornamented in scroll design and has the draft-openings l conforming to the line of ornamentation. Located above and

overhanging the openings in the draft-door is the panel L', carrying the scroll-and-leaf ornamentation, as shown. Above the draft-door on the front end of the range is the feed or broiling door M, carrying an open scroll-and-leaf ornamentation. 45

Having thus fully described my invention, what I claim as new, and desire to secure by 50 Letters Patent, is—

1. In a design for a stove or range, the design for the base; substantially as herein shown and described. 55

2. In a design for a stove or range, the design for the oven-door; substantially as herein shown and described.

3. In a design for a stove or range, the design for the oven-shelf; substantially as herein shown and described. 60

4. In a design for a stove, or range, the design for the reservoir; substantially as herein shown and described.

5. In a design for a stove or range, the design for the fire-door; substantially as shown 65 and described.

6. In a design for a stove or range, the design for the panel J, substantially as shown and described.

7. In a design for a stove or range the design for the ash-cup K, substantially as shown 70 and described.

8. In a design for a stove or range, the design for the front draft-door; substantially as herein shown and described. 75

9. In a design for a stove or range, the design for the broiling-door; substantially as herein shown and described.

10. The design for a cooking stove or range, substantially as herein shown and described. 80

BRADLEY WOODHULL.
